E. P. & J. A. COWLES.

Churn.

No. 16,717.

Patented March 3, 1857.

UNITED STATES PATENT OFFICE.

E. P. COWLES AND J. A. COWLES, OF OAKFIELD, NEW YORK.

CHURN.

Specification of Letters Patent No. 16,717, dated March 3, 1857.

To all whom it may concern:

Be it known that we, E. P. Cowles and J. A. Cowles, of Oakfield, in the county of Genesee and State of New York, have invented a new and Improved Churn; and we do hereby declare that the following is a full, clear, and exact description of the same, reference being had to the annexed drawing, making a part of this specification, said drawing being a vertical section of our improvement.

To enable those skilled in the art to fully understand and construct our invention, we will proceed to describe it.

15 A represents the body of the churn which is of cylindrical form and placed upon supports (a) (a) the axis of the cylinder being in a horizontal position.

20 B represents a shaft which runs horizontally through the body A. To one end of this shaft radial arms (a¹) are attached and to the inner surfaces of the arms (a¹) beaters (b) are attached, said beaters forming right angles with the arms. These beaters 25 are of somewhat curved form as shown clearly in the drawing.

C represents a shaft which is placed loosely on the shaft B so that it may rotate freely thereon and to this shaft radial arms 30 (c) are attached which have beaters (d) attached to their inner sides. The beaters (d) are also curved the same as the beaters (b) but in a reverse or opposite direction.

35 The outer surfaces of the arms (a¹) (c) are beveled or rounded on the sides facing their planes of rotation as shown at (e) (e). One end of the shaft B has a toothed wheel D upon it to which wheel a crank E is attached. This wheel D gears into a pinion 40 F which is placed on the upper end of a small shaft G attached to the outer side of the body A and rendered adjustable or capable of being moved up and down so that it may be thrown either in or out of gear with 45 the wheel D when desired. This adjustment is obtained by causing the lower end of the shaft G, to rest upon a button G¹. By merely turning the button aside, the shaft G falls, and is disengaged from the wheels 50 H, D. On the outer end of the shaft C a toothed wheel H is placed, said wheel gearing into the pinion F. The inner end of the

shaft C bears against a collar (f) on the shaft B and is kept snugly against it by a spiral spring (g) on the shaft B between the 55 two wheels D, H. A slight friction is thus produced between the collar (f) and the shaft C; so that when the pinion F is disengaged, the two shafts B, C, will rotate in the same direction, for the purposes before 60 described. Leakage between shafts B, and C, is also prevented by the collar (f). A shoulder or collar (h) is also on the outer end of the shaft C, said shoulder being kept snugly against the outer side of the body A 65 by a spring (i) the pressure of which may be graduated by a set screw (j). The object of pressing the collar (h) up against the machine is to prevent leakage at the aperture through which the shaft C passes. 70

When the pinion F is in gear with the wheels D, H, and the shaft B is rotated the two sets of arms (a¹) (c) with their beaters attached will rotate in opposite or reverse directions the arms and beaters forming 75 dashers which act upon the cream. The beaters (b) (d) owing to their curved form throw the cream from the center toward the sides of the body A.

We distinctly disclaim the invention of 80 two dashers, moving in contrary directions, and operated by geared wheels and an intermediate pinion. Examples of such an arrangement are seen in Brown & Bigelow's patent, 1852, and in Mansfield and Moore's 85 rejected application, 1853. But in neither of these examples, nor in any other churn with which we are acquainted, is our feature seen, of having the arms of the dashers so curved as to draw the cream from the center of the churn, and force it against the sides of the machine, for the purposes set forth. We disclaim the use of curved arms except when thus employed and operating. Having the connecting pinion F, adjustable, 90 in the manner and for the purposes described, is also a new and highly valuable feature in this description of churning. Without this adjustability, it would be almost impossible to collect the butter. The employment of springs, (g) and (i) saves the necessity of stuffing boxes, to prevent leakage. These features are also new in churning, to 95 the best of our knowledge and belief. 100

We disclaim every part and feature of our device, which is seen in any other churn or analogous machine. But

5 We claim, and desire to secure by Letters Patent,—

The shafts B, C, with collars (f) (h) and wheels D and H thereon, in combination with springs *i* and (g) arranged and

operating in the manner and for the purposes set forth.

E. P. COWLES.
